UNITED STATES PATENT OFFICE.

THOMAS WALL, OF BROOKLYN, NEW YORK, ASSIGNOR TO HIMSELF AND
ROBERT SEALY, OF SAME PLACE.

LAMP-BURNER.

SPECIFICATION forming part of Letters Patent No. 440,078, dated November 4, 1890.

Application filed January 24, 1889. Serial No. 297,437. (No model.)

To all whom it may concern:

Be it known that I, THOMAS WALL, of the city of Brooklyn, county of Kings, and State of New York, have invented a new and useful Improvement in Lamp-Burners, of which the following, taken in connection with the accompanying drawings, is a full, clear, and accurate description.

In the drawings, Figure 1 represents a side view of the improved burner complete. Fig. 2 is a section of the improved burner on the line $x x$ of Fig. 3. Fig. 3 is a plan view of the invention. Fig. 4 is a vertical section on the line $4 4$, Fig. 1.

15 Similar letters of reference refer to similar parts.

My invention relates to burners for street-car lamps. Owing to the peculiar construction of the lamp-boxes used on street-cars it is necessary that the lamp-founts shall be made about twice as long as they are wide. On the inside and back end of the lamp-box are reflectors placed at an angle, and in order to obtain the full candle-power of the light 25 from the lamp it is necessary that the burner should be adjusted to the lamp-body in such a manner that the wick-tube shall stand parallel with the length of the lamp-fount. The lamp-burners now in use on street-cars 30 are adjusted to the lamp-fount by means of screw-threads cut on the lower portion of the burner and corresponding screw-threads cut on the collar of the lamp-fount, so that when the burner is securely fastened to the lamp-fount it will often happen that the wick-tube 35 will be at an angle instead of being parallel with the length of the lamp-fount, as it properly should be.

The object of this invention is to construct 40 a lamp-burner so that at all times the wick-tube can be adjusted parallel with the length of the lamp-fount. I effect this by making that portion of the burner bearing the screw-thread an independent piece, held in the cap 45 covering the bottom of the burner, and providing means by which said independent screw-thread piece can be turned in said cap, and when adjusted to the right position held firmly in said position.

50 In the drawings, A represents the independent screw-threaded piece fitting loosely

into the cap B. This piece A is provided with a flange a cut into cogs or teeth a' , as shown in Fig. 3. The cap B is provided with a rim b , upon which the flange a rests, and it 55 is also provided with a stop or lug C of a size to fit loosely between the cogs a' of the piece A. The springs S, serving to hold the chimney in its place, press with their lower edges against and upon the flange a , which serves 60 to keep the piece A in position when adjusted, while there is play sufficient to enable said piece A to be adjusted in position. When detached from the lamp, this play is given by removing the cap H surrounding the wick-tube, and which when in its place forces the 65 springs S into position firmly against the outer case of the burner D, also against the flange a of the piece A.

The operation of my invention is as follows: The pieces of the burner being in position as shown in Figs. 1 and 2, the burner is screwed upon the lamp-fount. If it so happens, as it almost always will be the case, that the wick-tube, when the burner is screwed 70 tightly on the lamp-fount, is at angle with its length, that the burner should be removed from the lamp-fount and the piece A adjusted, this is accomplished by first removing the cap H, which, as before said, loosens 75 the tension of the springs S upon the piece A. The piece A is then pressed upward until the flange a passes above and is clear of the lug C. The piece A is then turned slightly so as to bring the space between other cogs than 80 was originally the case in line with and over the lug C. The piece A is then pulled down, allowing the lug C to fit between this space, and the cap H being adjusted, it would be 85 found upon screwing the burner to the lamp-fount that the angle at which the wick-tube 90 stands has been changed. This operation can be repeated until it is found that the wick-tube when the burner is adjusted to the lamp-fount is parallel to the length of the said 95 lamp-fount. A very little practice will enable one to make this adjustment at the first operation.

Having thus described my invention, what I claim as new, and desire to secure by Letters Patent, is—

1. A lamp-burner provided with a screw-

threaded piece having a cog-flange held loosely in position in the lower portion of the burner by means of a rim on said lower portion, having a stop or lug fitting between the 5 cogs of said screw-threaded piece, said cogged flange being held firmly in position by the pressure of the lower ends of the chimney-holding springs, as described and shown.

2. A lamp-burner provided with a screw-threaded piece A, having a flange *a* and cogs

a', the cap B, having a rim *b*, and lug C, springs S, and cap H, arranged as shown and described.

In testimony whereof I have hereunto set my hand this 5th day of July, 1888.

THOMAS WALL.

In presence of—

LOUIS W. FROST,
ROBERT SEALY.
